DESIGN FOR A DIRECTIONAL SIGNAL LAMP FOR VEHICLES

Abraham Hollins and Jesse Hollins, Brooklyn,
N. Y.

Application April 28, 1937, Serial No. 69,022

Term of patent 14 years

To all whom it may concern:

Be it known that we, Abraham Hollins and Jesse Hollins, both citizens of the United States and residents of the Borough of Brooklyn, county of Kings, city and State of New York, have jointly invented a new, original, and ornamental Design for a Directional Signal Lamp for Vehicles, of which the following is a specification, reference being had to the accompanying drawing, forming part thereof.

In which

Figure 1 is a front elevational view of a directional signal lamp for vehicles, showing our new design; and

Figure 2 is a plan view thereof.

Figure 3 is a rear elevational view thereof.

We claim:

The ornamental design for a directional signal lamp for vehicles, as shown.

ABRAHAM HOLLINS.
JESSE HOLLINS.
